UNITED STATES PATENT OFFICE

THEODORE H. WITTLIFF, OF CLEVELAND, OHIO

FURNITURE BRACE AND CONTROL THEREFOR

Application filed May 14, 1925. Serial No. 30,155.

This invention as indicated relates to a furniture brace and control therefor. More particularly it comprises a plurality of flexible elements associated with the frame of an article of furniture and having a central tensioning device which may be adjusted to the desired degree of tension from a point external to said article of furniture. The apparatus is intended more particularly for application to a bed, but obviously it would be of equal utility used in connection with other articles of furniture such as a desk, table, davenport or the like.

Bedsteads having a central tensioning means have heretofore been known, but in each instance it has been necessary to tension the device directly. In many instances the tensioning device is in an inaccessible position and difficulty is experienced in applying exactly the desired amount of tension thereto. The present invention has in view the provision of means which may at all times be readily accessible, whereby any desired degree of tension may be applied to the furniture brace. At the same time the device is so arranged that it will normally be kept in a concealed position beneath the article of furniture. It may be, however, readily drawn to a position where it may be easily operated to effect the purpose stated. This is particularly desirable where the bed brace is to be operated by women of the household, who have small mechanical knowledge. The device is also arranged so that ample leverage is provided so that a minimum of effort will serve to adjust the furniture brace with the requisite amount of tension. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but several of various mechanical forms in which the principle of the invention may be used.

In said annexed drawings, Fig. 1 is a top plan view showing one form of an improved furniture brace and the control therefor; Fig.

2 is a view similar to Fig. 1 showing the use of looped flexible elements for connecting the brace to the frame of the article of furniture; Fig. 3 is an enlarged side elevation partially in section of the form of tensioning device shown in Figs. 1 and 2; Fig. 4 is an enlarged perspective view of one of the grooved tensioning blocks adapted to be engaged upon the shaft of the tensioning device; Fig. 5 is a view similar to Fig. 4, showing one of the tensioning blocks having the crossed cables engaged within a single groove thereof; Fig. 6 is a view similar to Figs. 4 and 5, but showing the crossed cables in separate grooves of the tensioning block; Fig. 7 is a top plan view showing a modified form of furniture brace and control therefor; Fig. 8 is a top plan view showing still another modified form of furniture brace and control therefor; Fig. 9 is an end view taken along the line 9—9 shown in Fig. 8 looking in the direction of the arrows; Fig. 10 is a top plan view of a tensioning device of still another modified form, and Fig. 11 is an enlarged detail sectional view taken along the line 11—11 shown in Fig. 7.

In the form of construction shown in Fig. 1, the furniture brace is shown as applied to the frame 1 of a wooden bedstead. The corner posts 2 of said bedstead are joined by side rails 3 and end members 4. A cross bar 5, may serve to space the side members adjacent the central portion of said frame. At each inner corner of the respective posts a hook shaped member 6 is secured and similar members 7 are secured to the inner sides of the side rails adjacent the center portion thereof. A flexible member 8, preferably provided with terminal chain links 9 is engaged by means of said links with the respective hooks 6 at one end of the bed frame. A pair of flexible members 11, 12, similar in construction to the flexible member 8, are secured at one end to the respective end posts opposite those first referred to, and thence cross each other and extend to the opposite hooks positioned at the central portions of the side members. The central portions of said flexible members are engaged respectively over blocks 13, 14, supported upon a shaft 15 of a

central tensioning device. The blocks may be of any desired configuration except that the forward portions are preferably provided with a pair of inclined faces 16, 17 across which upper and lower grooves 18, 19 are provided. A transverse screw-threaded opening 21 is formed centrally through each of said blocks. The block 13 is preferably provided with a transverse bore of larger diameter than that of the block 14 in order to permit the same to be engaged upon the heavier portion of the shaft 15 of the tensioning device. The shaft 15 of the tensioning device as is clearly shown in Fig. 3 comprises a member having a screw threaded forward end. The forward end 22 of said member is of reduced diameter and carries right handed screw threads. The inner portion 23 of said member is of larger diameter and carries left handed screw threads. The screw threads on the section of larger diameter are adapted to be engaged by the tensioning block 13 and the other screw threads by the tensioning block 14. The inner end of the shaft 15 is adapted to be received within a sleeve 24 which is provided with an elongated slot 25. A screw 26 set into the side of the member 15 adjacent its inner end is engaged through the slot 25 of the sleeve and serves as a guide and limiting stop therefor. A crank handle 27 is provided at the other end of the sleeve, and is firmly secured therein by any suitable means.

In the form of construction shown in Fig. 35 the central portion of the flexible member 8 is engaged in the upper groove of the block 13. The flexible members 11 and 12 may be engaged in the block 14 in the manner illustrated in Fig. 5 wherein the members are 40 both placed in the upper groove of the block, or in the manner shown in Fig. 6 wherein the member 11 is placed in the upper groove 18 and the member 12 is placed in the lower groove 19.

45 It has also been found desirable in many instances to use a closed loop type of flexible member. In such construction the flexible loop 31 has its respective central portions engaged within the grooves 18 and 19 of the block 13, and the central portions of each of the loops 32 and 33 are engaged within the grooves 18 and 19 respectively of the block 14. Thus each of said grooves carries flexible elements in the manner illustrated in Fig. 55 in connection with the upper groove 18.

It may be found desirable to use looped or flexible elements over one of the tensioning blocks and single flexible elements over the opposite blocks, and likewise where very 60 heavy tension is to be applied, duplicated elements of the character shown in Fig. 1, that is, two of each of the flexible members 8, 11 and 12 may be employed in place of the single flexible members illustrated. In the form 65 of construction shown in Fig. 7 a different

type of tension device is illustrated. In said construction the tensioning screw shaft 41 is provided with right handed screw threads 42 upon one end, and left handed screw threads 43 upon the opposite end, which screw threads are engaged by cable receiving yoke members 44, 45 respectively. Said yoke members, as is more particularly illustrated in Fig. 11 are each provided with curved body members 46 and upper and lower flanges 47, 48. Over each of said yokes as shown in Figs. 7 and 11, a single flexible member 51 may be placed, or if a high degree of tension is to be applied to the frame, a pair of parallel flexible members may be secured to the respective end posts of the frame structure, with the middle portions thereof engaged with the yoke members above and below the threaded shaft of the tensioning device. The yoke members may be engaged with flexible members identical with those shown in either Figs. 1 and 2, or may be of the type illustrated in Fig. 7 wherein the ends of said respective flexible members 51 are provided with eyes which are engaged over the hook members 6.

The means used for tensioning the device shown in Fig. 7 will be described in connection with the construction shown in Figs. 8 and 9. In Fig. 8 the tensioning device instead of being provided with yoke shaped tensioning members is provided with rectangular plates 52 provided with notches 53 on their longer sides adjacent their ends of a size suitable to receive the central portions of the flexible members. The flexible members may be in the form of loops 54 as shown in Fig. 8 or may be similar to the flexible member 8 shown in Fig. 1, or the flexible member 51 shown in Fig. 7, each of the ends of said members, however, being fastened to the same hook when used with a plate of the character shown in Fig. 8. The side edges 55 of the plates 52 may be bent at a slight angle so as to permit the flexible elements to pull at substantially right angles to their point of attachment. The outer ends of the loop 54 are engaged over the hooks 6 in the manner clearly shown in Fig. 9. Each of the plates is provided with a central aperture 56, which is appropriately screw threaded to engage the adjacent end of the tensioning shaft. The means for operating the tensioning shaft is clearly disclosed in Fig. 9 and comprises a worm wheel 61 rigidly secured to the shaft 41 and having its peripheral teeth engaged with a worm 62 carried at the outer end of a telescopic crank shaft 63 identical in construction at its outer end with the crank shaft illustrated in Fig. 3 of the drawings. Thus, it is provided with a sleeve 64 having a longitudinal slot 65 engaged over a screw 66, which serves as a guide pin and limiting stop. The outer end of the sleeve has a crank handle 67 firmly engaged therewith.

The telescopic crank shaft need not be of the same length as the devices shown in Figs. 1, 2 and 3, inasmuch as it is intended to project laterally toward the side of the bedstead, or 5 other article of furniture rather than toward the end thereof. The worm is held in engagement with the worm wheel by means of a stirrup plate 71 having upwardly turned ears 72, suitably apertured to fit over the 10 shaft 63 on either side of the worm, and having a pair of up-standing ears 73 to engage over the tensioning shaft 41 on either side of the worm wheel. While the frictional engagement with the worm wheel may be adequate 15 to maintain the crank arm in horizontal position beneath the bedstead, it may be found desirable to hook the outer end of the crank arm to the adjacent side rail by means of a pivoted hook 75 or some similar device 20 as is shown in Fig. 8.

The tensioning device as illustrated in Figs. 1, 2 and 3 includes a screw threaded shaft of two dimensions.

In Fig. 10 a form of construction is illustrated in which one of the yoke members 81 is movable longitudinally of the screw threaded shaft 82, and the other yoke member 83 is held against longitudinal movement. Said yoke member is held against a 30 washer 84 which bears against a shoulder 85 formed on the screw threaded shaft at approximately the mid-length thereof by means of a second washer 86, which is prevented from moving forwardly by means of a cotter 35 pin 87 or any equivalent device. The other end of the telescopic crank shaft is identical in construction as that illustrated in Fig. 3 and the parts bear corresponding reference characters.

40 The tensioning device shown in Fig. 10 may be used with flexible members of any of the forms shown in Figs. 1, 2 and 7 or any desired combination of said flexible members.

The flexible elements used may be single 45 strand or multi-strand and may have integral eyes formed at the ends thereof, or may be provided with short chain sections which will permit of a certain latitude of adjustment independently of the tensioning device.

50 Other modes of applying the principle of my invention may be employed instead of the one explained, change being made as regards the means and the steps herein disclosed and the forms of the product resulting 55 therefrom, provided those stated by any one of the following claims or their equivalents be employed or embodied therein.

I therefore particularly point out and distinctly claim as my invention:

60 1. A brace of the character described comprising corner-stays, a saddle, a closed wire loop whose extremities are mounted upon said corner-stays and whose intermediate portion passes over said saddle to provide a 65 pair of wire strands between said corner-

stays, and a bolt for adjustably securing said saddle in position so as to exert a strong pull upon said corner-stays, said bolt also serving to maintain the strands out of contact with each other on the saddle. 70

2. A brace of the character described comprising two pairs of corner-stays, a saddle for each pair of corner-stays, a closed wire loop for each pair of corner-stays whose extremities are mounted upon their associated 75 corner-stays and whose intermediate portions pass over the corresponding saddles to provide a pair of wire strands between each pair of corner-stays and a bolt for relatively adjusting said saddles in position so as to 80 exert a strong pull upon said corner-stays, said bolt also serving to maintain the strands out of contact with each other on the saddle.

3. A brace of the character described comprising corner-stays, a saddle, a closed wire 85 loop whose extremities are mounted upon said corner-stays and whose intermediate portion passes over said saddle to provide a pair of wire strands between said corner-stays, and means for adjustably securing said saddle in position so as to exert a strong pull upon said corner-stays, said saddle consisting of a runway for the wire loop and side walls to retain said wire loop in position, said 90 securing means separating the strands on the 95 saddle.

4. A brace of the character described comprising two pairs of corner stays, a saddle for each pair of corner stays, a wire loop for 100 each pair of corner stays whose extremities are mounted upon their associated corner stays and whose intermediate portions pass over the corresponding saddles to provide a pair of wire strands between each pair of corner stays, each strand of said pairs of 105 wire strands being spaced from the other upon their corresponding saddles whereby one strand may move relative to the other of a pair without friction therebetween and tensioning means for drawing said saddles toward each other. 110

Signed by me this 9th day of May, 1925.
THEODORE H. WITTLIFF.
